Specification for Design.

Patented Dec. 12, 1916.

Application filed March 1, 1916. Serial No. 81,563. Term of patent 7 years.

To all whom it may concern:

Be it known that I, FREDERICK KAUPMANN, a citizen of the United States, residing at Brooklyn, in the county of Kings, in the State of New York, have invented a new and original and ornamental Design for Spoons, Forks, and the like, of which the following is a specification, reference being had to the accompanying drawing, forming a part thereof.

In said drawing: Figure 1 is a front view of my design for spoons, forks and the like; Fig. 2 is a back view of the same; Fig. 3 is a cross sectional view of the end portion of the handle of the same.

I claim:

The ornamental design for a spoon, fork or the like, as shown.

FRED'K. KAUPMANN.
